CLAIM

The ornamental design for a combined rake and pitchfork, substantially as shown and described.

DESCRIPTION

FIG. 1 is a perspective view of a combined rake and pitchfork showing my new design;

FIG. 2 is a top plan view thereof;

FIG. 3 is a bottom plan view thereof;

FIG. 4 is a front end elevational view thereof;

FIG. 5 is a rear end elevational view thereof; and

FIG. 6 is a right side elevational view thereof, the left side being a mirror image.
